MAGNETRONS

John Edwin Baker, London, and Harold Alexander Cecil Hogg, Kenton, and Eric Kettlewell, Ruislip, England, assignors to The M-O Valve Company Limited, London, England

Application January 16, 1956, Serial No. 559,423

3 Claims. (Cl. 315—39.77)

This invention relates to magnetrons of the type having an anode in the form of a metal block with parallel end faces which is pierced perpendicularly to said end faces both by a cylindrical electron orbit hole, within which is supported the cathode of the magnetron, and by a plurality of slots opening into said hole, which slots constitute a plurality of cavity resonators separated by anode segments evenly spaced around the axis of said electron orbit hole, and including output coupling means which introduces into the anode resonator system a plane of symmetry containing the axis of the electron orbit hole. Such output coupling means may consist, for example, of a coupling loop projecting into a single cavity resonator or of an extension of one of said cavity resonator slots to the exterior of the anode block as part of a wave-guide output system. The term "metal block" does not necessarily imply that the block is constructed in one piece—it may in some cases consist of a number of parts soldered or otherwise attached together; also the block need not necessarily be solid—it may, for example, contain channels for the passage of cooling fluid.

In magnetrons of this type the anode is usually provided at each end face with two concentric coupling rings of which one ring is connected to each of one set of alternate anode segments and the other ring is connected to each of the other, interleaved, set of anode segments. We have found that advantages are obtained if each of the said four coupling rings is broken at one place, and at each end of the anode the breaks in the two coupling rings at that end are disposed on radii which are on opposite sides of and are equally inclined to the plane of symmetry introduced into the anode resonator system by the output coupling means. Preferably the output coupling means is associated with a single cavity, for example as a coupling loop entering the cavity or as a slot extending from the back of the cavity to the exterior of the block as part of a wave-guide output system, and the breaks in the coupling rings are made each on the side of the anode opposite to said single cavity and where the ring passes over that one of the anode segments to which it is not connected which lies nearest to said plane of symmetry, said plane passing through said single cavity.

The advantages obtainable by this construction are an increase in the stability of π -mode oscillation of the magnetron and/or a quicker rate of build-up of oscillations in the wanted π -mode when the magnetron is subjected to pulsed operation.

In such a magnetron the anode supporting structure usually has the form of a metal block recessed from opposite end faces to form a central partition with end spaces on each side thereof, the central partition being pierced by the electron orbit hole and resonator slots to provide the anode.

We have further found that in a magnetron of this form the end spaces are coupled with the anode resonator system, so that the end spaces and the anode system resonate together as a whole, and we have discovered

2

that the frequency of this resonance, and hence the output frequency of the magnetron, can be simply controlled over an appreciable range by varying the internal dimensions of the end spaces.

In addition by suitable adjustment of the dimensions of the end spaces, the advantages as regards π -mode stability and quick rate of build-up of oscillations into the π -mode, resulting from the presence of breaks in the coupling rings at each end of the anode, can be enhanced. To explain this, it may be stated that the main cause of instability of π -mode oscillation of known magnetrons has resulted from the fact that in pulse operation the magnetron usually starts to oscillate, at the beginning of each pulse, in the $(\pi-1)$ mode and then changes over to the π -mode as the anode current increases; in some cases, however, operation in the unwanted $(\pi-1)$ mode persists to high current levels, with the result that operation in the π -mode is impaired, or may even be absent altogether. The $(\pi-1)$ mode is driven by its reverse component whose threshold voltage lies below that of the π -mode so that it is excited before the π -mode.

We have found that the effect of the discontinuities introduced by the coupling ring breaks provided at each end of the anode is to alter the relative amplitudes of the space harmonics contained in the space pattern of the electric field set up by the oscillating anode system. We have further found that by varying the dimensions of at least one of the end spaces, the amplitudes of the space harmonics of the electric field pattern can be controlled so that a relatively large amplitude is obtained for the $(\pi+1)$ space harmonic of the π -mode field pattern, and that as the threshold voltage of the said $(\pi+1)$ space harmonic of the π -mode field, which is below the threshold voltage of the reverse component of the unwanted $(\pi-1)$ mode, is reached at the beginning of each operating pulse. The anode system starts to operate at the π -mode frequency on this π -mode field harmonic; because the π -mode field pattern is thus established, further increase of the voltage then causes the anode system to change readily into the fundamental π -mode operation without change of frequency and with little or no interference from the $(\pi-1)$ mode. Both the starting and continuation of oscillations at the π -mode frequency are thereby facilitated.

Accordingly, therefore, the present invention provides a method of manufacture of a magnetron of the kind referred to wherein the anode supporting structure has the form of a metal block recessed from each end face to form a central partition with end spaces on each side thereof, the central partition being pierced by the electron orbit hole and resonator slots to provide the anode, and being provided at each end face with two concentric coupling rings each broken at one place, which method of manufacture includes the step of adjusting the internal dimensions of at least one end space so as to increase the amplitude of the $(\pi+1)$ harmonic of the space pattern of the electrical field set up by the anode system when oscillating in the π -mode to obtain the dimensions at which the amplitude of the said harmonic is sufficiently large to ensure that reliable oscillation of the magnetron in the π -mode is obtained in pulse operation of the magnetron.

In carrying out a manufacture in accordance with the invention, the space pattern of the electrical field distribution set up by the anode system when oscillating in the π -mode can, if required, be determined experimentally, and the amplitude of the $(\pi+1)$ harmonic ascertained by a Fourier analysis, for each adjustment of the end space dimensions, but as this is a tedious process it will in practice usually be more convenient to judge the effect of a variation in the end space dimensions by observing

the performance, as regards mode stability, of the magnetron by measurement of its output frequency, the end space dimensions being regarded as suitably adjusted when good mode stability is obtained.

Our present experience is that the amplitude of the said $(\pi+1)$ harmonic should preferably be about 10% of the amplitude of the fundamental, but this is not critical and may be much less in some cases.

It will be appreciated that the main utility of the invention lies in the adjustment of the end space dimensions in the design of a prototype of a magnetron, which may involve the construction of a number of magnetrons of the same kind which have different values of the said end space dimensions; once the optimum dimensions have been obtained, the construction of numbers of magnetrons to the established design including the optimum dimensions can then proceed without need for individual adjustment of this kind in their construction.

It will also be appreciated that an adjustment of the end space dimensions will also alter the operating frequency of the magnetron, but allowance can be made for this in the design of the magnetron by a suitable adjustment of the dimensions of the anode resonant cavities; we have found, in general, that a change in the frequency of the π -mode resulting from the adjustment of the end space dimensions produces also a substantially equal change in the frequency of the unwanted mode, so that the disturbing effect of the unwanted mode is not increased by its frequency separation from the π -mode being reduced.

We found that the most convenient way of adjusting the end space dimensions in a method of manufacture in accordance with the invention is to vary the effective internal diameter of the end space, and that this can be conveniently adjusted by altering the depth and/or width of an annular groove, formed in the side-wall bounding the end space, concentric with the axis of the end space.

One magnetron which has been manufactured by a method in accordance with the invention is illustrated by way of example in the accompanying schematic drawing, which shows a section in a plane containing the axis of the magnetron, and the invention will be further described with reference to this drawing.

The magnetron shown in the drawing has a rectangular copper anode block 1 provided round three sides with a channel 2 for the passage of cooling fluid. The block is pierced between its two major end faces by a cylindrical aperture which is of somewhat smaller diameter at the centre of the block to form a seating for the attachment of radial copper anode segments 3 the spaces between which form the anode cavity resonators and the opposed inner ends of which define the cylindrical electron orbit space of the magnetron. The anode segments effectively form a central partition in the anode block having cylindrical end spaces 4 and 5 on each side thereof.

Into one side of the block is spigotted, radially with respect to the anode, a cylindrical metal annulus 6 the space within which communicates with one of the anode cavity resonators through two holes 7 and 8 in the side of the block, along which holes pass output leads 9 and 10 which terminate in coupling loops 11 and 12 within the said resonator, the loops being oriented oppositely with respect to each other. The leads 9 and 10 are continued by sleeves 13 and 14 into which they slidably fit and which are connected together at their outer ends by a bridge piece 15 to form an output coupling loop. The loop is supported by a sleeve 16 extending from the centre of the bridge piece slidably over a support rod 17 spigotted into a bushing 18 fitted into the bottom part of the annulus 6. The sleeves 13, 14 and 16 permit the length of the output loop to be adjusted to the optimum value in assembly of the magnetron and are thereafter fixed to the leads 9 and 10 and rod 17, respectively. The upper part of the annulus 6 is attached to a cylindrical metal flange 19 which is hermetically closed by a glass-to-metal

dome seal 20 of known kind and also carries a metal cylinder 21 which surrounds the dome 20 and forms part of a waveguide output connection.

The cathode of the magnetron consists of a hollow metal tube 22 having a central region of reduced outer diameter forming a recess in which is provided the electron emissive material 23. The tube 22 is of expanded internal and external diameter at each end and is covered on its external surface at each of these ends with a thin skin 24 of a metal of high thermal emissivity. The tube 22 is supported at one end from a metal tube 25 which is in turn supported from an end plate 26, closing the corresponding side of the anode block, by means of the glass sleeve 27 sealed at one end to the tube 25 and at the other end to a metal tube 28 spigotted into the end plate 26.

The cathode heater 29 is arranged within the cathode tube 23 and is supported at one end by a metal rod 30 which passes along the tube 25 and is in turn supported 20 therefrom by the insulating spacer 31 and glass button 32 which seals the space between the rod 30 and tube 25. The other end of the heater is supported from an annular insert of magnetic material 33 which is fitted into the expanded end of the tube 23 for improving the uniformity of the operating magnetic field within the electron orbit space in use of the magnetron. A similar insert 34 is provided within the other expanded end of the tube 23, for the same purpose. The tube 25 and rod 30 provide also the cathode and heater supply connections.

The side of the anode block opposite to that through which the cathode and heater support and supply means are taken is closed by the attachment thereto of an end plate 35 into the centre of which is spigotted a metal dome 36 which extends over the corresponding end of the cathode tube 23.

The space within the magnetron is evacuated and sealed off by means of an exhaust stem (not shown), holes 37 and 38 being provided through the wall of the anode 40 block between the end spaces 4, 5 and the interior of the output means for facilitating the exhaustion in manufacture of the magnetron.

The anode segments 3 are provided at each end with two concentric mode-locking rings 39, 40 and 41, 42 respectively, which are each broken at one point; the effect of these breaks is to include the end spaces 4 and 5 within the resonant anode system and in accordance with the present invention the effect of these end spaces is controlled for obtaining good stability of pulse operation 50 of the magnetron in the π -mode by providing in the wall of the block bounding each end space an annular groove 43 and 44 respectively whose width and depth have optimum values as determined by trial in the design of the magnetron, as previously explained.

We claim:

1. In the manufacture of a resonant cavity magnetron having an anode supporting structure in the form of a metal block recessed from each end face to form a central partition with cylindrical end spaces on each side thereof, the central partition being pierced by the electron orbit hole and a plurality of resonator slots to provide the anode, the cathode of the magnetron being supported within the electron orbit hole, an output coupling means being provided on one side of the anode so as to introduce into the anode system a plane of symmetry containing the axis of the electron orbit hole, and the anode being provided at each end face with two concentric coupling rings of which one ring is connected to each of one set of alternate anode segments and the other ring is connected to each of the other set of anode segments, each of the said four coupling rings being broken at one place, and at each end of the anode the breaks in the two coupling rings at that end being disposed on radii which are on opposite sides of and are equally inclined to the plane of symmetry introduced into the anode resonator

system by the output coupling means: that improvement including the step of providing an annular groove coaxial with the electron orbit hole in the cylindrical side wall of at least one end space and adjusting the dimensions of the groove so as to increase the amplitude of the $(\pi+1)$ harmonic of the space pattern of the electrical field set up in the electron orbit space by the anode system when oscillating in the π -mode until groove dimensions are obtained at which the amplitude of the said harmonic is sufficiently large to ensure that reliable oscillation of the magnetron in the π -mode is obtained in pulse operation of the magnetron.

2. A method according to claim 1 wherein together with adjustment of the dimensions of at least one annular groove in an end space there is effected a concurrent adjustment of the dimensions of another part of the anode resonator system for maintaining the same operating frequency for the magnetron.

3. A resonant cavity magnetron having a sealed evacuated envelope containing an anode supporting structure 20 in the form of a metal block recessed from each end face to form a central partition with cylindrical end spaces on each side of the partition, the central partition being pierced by a coaxial hole which provides the electron orbit hole and by a plurality of slots extending radially 25 from said hole which provide the anode resonators, a cathode supported coaxially within the electron orbit hole, conducting paths to the anode and cathode extend-

5
10

ing to the exterior of the envelope, an output coupling means provided on one side of the anode which introduces into the anode system a plane of symmetry containing the axis of the electron orbit hole, on each end face of the anode two concentric coupling rings of which one ring is connected to one set of alternate anode segments and the other ring is connected to each of the other set of anode segments, each of the said four coupling rings being broken at one place, and at each end of the anode the breaks in the two coupling rings at that end being disposed on radii which are on opposite sides of, and are equally inclined to, the plane of symmetry introduced into the anode resonator system by the output coupling means, and in the cylindrical side wall of at least one end space a coaxial annular groove of dimensions critically adjusted to produce π -mode oscillation of the magnetron in pulse operation without any component of the $(\pi-1)$ mode frequency appearing in the magnetron output.
